(57) **CLAIM**

The ornamental design for a bottle, as shown and described.

DESCRIPTION

FIG. 1 is a front perspective view of a first embodiment of the bottle;

FIG. 2 is a rear perspective view of the bottle of FIG. 1;

FIG. 3 is a front elevation view of the bottle of FIG. 1;

FIG. 4 is a rear elevation view of the bottle of FIG. 1;

FIG. 5 is a left side view of the bottle of FIG. 1;

FIG. 6 is a right side view of the bottle of FIG. 1;

FIG. 7 is a top view of the bottle of FIG. 1;

FIG. 8 is a front perspective view of a second embodiment of the bottle;

FIG. 9 is a rear perspective view of the bottle of FIG. 8;

FIG. 10 is a front elevation view of the bottle of FIG. 8;

FIG. 11 is a rear elevation view of the bottle of FIG. 8;

FIG. 12 is a left side view of the bottle of FIG. 8;

FIG. 13 is a right side view of the bottle of FIG. 8;

FIG. 14 is a top view of the bottle of FIG. 8;

FIG. 15 is a front perspective view of a third embodiment of the bottle;

FIG. 16 is a rear perspective view of the bottle of FIG. 15;

FIG. 17 is a front elevation view of the bottle of FIG. 15;

FIG. 18 is a rear elevation view of the bottle of FIG. 15;

FIG. 19 is a left side view of the bottle of FIG. 15;

FIG. 20 is a right side view of the bottle of FIG. 15; and,

FIG. 21 is a top view of the bottle of FIG. 15.

Broken line disclosures in the figures are for illustrative purposes only and form no part of the claimed design.
